[57] CLAIM

The ornamental design for a vehicle tire, substantially as shown.

DESCRIPTION

FIG. 1 is a perspective view of a vehicle tire showing our new design, it being understood that the tread design is repeated throughout the circumference of the tire, the opposite side being substantially the same as that shown;

FIG. 2 is a front elevational view thereof;

FIG. 3 is a side elevational view thereof;

FIG. 4 is a sectional view taken along the line 4—4 of FIG. 2 in the direction indicated generally.

FIG. 1

FIG. 3

FIG. 2

FIG. 4
